CLAIM

The ornamental design for display panel for tape printing machine, as shown and described.

DESCRIPTION

FIG. 1 is a perspective view of a display panel for tape printing machine;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof;

FIG. 8 is a reduced scale front view thereof similar to FIG. 2 wherein a display panel is in a rotated position; and,

FIG. 9 is a reduced scale rear view thereof similar to FIG. 6 wherein the display panel is in another rotated position.

The broken lines are for illustrative purposes only and form no part of the claimed design.
